AU 292

EX

OF D 15,006

Design No. 15,006, dated May 20, 1884.

UNITED STATES PATENT OFFICE.

JOSEPHUS HARTMAN, OF PHILADELPHIA, PENNSYLVANIA.

DESIGN FOR A BISCUIT-CRACKER.

SPECIFICATION forming part of Design No. 15,006, dated May 20, 1884.

Application filed September 10, 1883. Term of patent 14 years.

To all whom it may concern:

Be it known that J. JOSEPHUS HARTMAN, a citizen of the United States, residing at Philadelphia, in the county of Philadelphia and State of Pennsylvania, have invented and produced a new and original Design for Biscuit-Crackers, reference being had to the accompanying photographic illustration, forming part thereof.

10 The accompanying photographic illustration represents a biscuit-cracker having in the center of its surface the representation of an oyster.

For the purpose of illustration a round biscuit is shown, having thereon the resemblance 15 of an oyster.

I claim—

The design for a biscuit-cracker having its upper surface centrally ornamented in imitation of an oyster, as shown and described.

JOSEPHUS HARTMAN.
